Primary Examiner — David G Muller*Assistant Examiner* — Christina Gabrielle Cosden(57) **CLAIM**

The ornamental design for a security bar for sliding door, as shown and described.

DESCRIPTION

FIG. 1 is a front, top perspective view of a security bar for sliding door, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view of the security bar for sliding door, shown in an alternative position; and,

FIG. 10 is a rear, bottom perspective view thereof.

The broken lines in the figures illustrate portions of the security bar for sliding door that form no part of the claimed design.

1 Claim, 10 Drawing Sheets(56)
